UNITED STATES PATENT OFFICE.

HARVEY H. SLATER, OF KENOSHA, WISCONSIN.

MULTIPLE-FILAMENT ELECTRIC-LAMP HEADLIGHT.

Application filed July 15, 1921. Serial No. 484,853.

To all whom it may concern:

Be it known that I, HARVEY H. SLATER, a citizen of the United States, residing at Kenosha, in the county of Kenosha and 5 State of Wisconsin, have invented certain new and useful Improvements in Multiple-Filament Electric-Lamp Headlights, of which the following is a specification.

My invention relates to headlights, search-lights, and similar appliances employing incandescent filament electric lamp bulbs and associated reflectors, but pertains more particularly, yet not exclusively, to lights of this general kind employed on automobiles.

With such equipments, it is desirable or essential to provide a powerful, piercing, bright light which will be projected a considerable distance without serious or material dispersion, and also to employ means for supplying a much dimmer light which will not dazzle or temporarily blind or inconvenience a person facing it.

The former intense light is ordinarily used for country driving, but since such brilliant and dazzling light, while well adapted for its purpose, is unsuited for city or town driving, the dimmer and less bright light is employed.

My improved and novel headlight structure is of the single bulb multiple filament type with two filaments, desirably though not necessarily of equal brilliancy, each located close to but not at the focus of the reflector, whereby either filament may be rendered incandescent for dim lighting, whereas both filaments may be simultaneously supplied with electric current for bright lighting. Preferably the two filaments are arranged symmetrically on opposite sides of the axis of the reflector near but neither at the focal center thereof. Owing to such slightly out-of-focus arrangement, when either filament is heated its light rays although more or less brilliant are sufficiently dispersed or dissipated so that a person facing the headlight is not at all inconvenienced. When the two filaments are rendered simultaneously incandescent, they in effect, due to their proximity to one another and to the focus of the reflector, in large measure form the equivalent of an incandescent filament at such focal center, producing a piercing brilliant light such as is required for some kinds of

automobile driving as explained above. The light rays absent when either filament alone is incandescent are supplied by the companion filament when both are heated at the same time.

Stated somewhat otherwise, the light beams of each filament form a complement of those of the companion filament, and compensate for its lack of focal brilliancy, the light rays from the two filaments 65 unitedly and conjointly functioning to produce the required effulgence and brightness equivalent to the use of a single filament of proper and adequate candle power at the focus of the reflector.

If for any reason, as by being burned out, either out-of-focus filament becomes useless or destroyed, the other can be used as a suitable substitute for reduced lighting effect.

To enable those skilled in this art to have a full and complete understanding of this invention and its various structural and functional advantages, I have illustrated a desirable and preferred embodiment of the invention in the accompanying drawing, the single figure of which shows an automobile headlight incorporating the invention in vertical section with the wiring illustrated more or less diagrammatically.

Referring to the drawing, it will be perceived that the improved headlight structure comprises a main, hollow, sheet-metal body 10 of the usual general parabolic or other appropriate shape equipped at its front with a round, protective glass 11 demountably or detachably held in place by any suitable or usual means.

Internally such sheet-metal body accommodates the customary polished reflector 12 equipped at its center with a rearwardly-extended lamp socket 13 of appropriate or any usual design permitting adjustment of the electric lamp bulb forwardly or backwardly for proper and correct positioning thereof.

Such socket is designed and adapted to receive and make suitable electric contact with the stem or base 15 of an electric lamp bulb 14 equipped internally with a pair of concentrated filaments 16 and 17 of equal light intensity when heated and arranged close to and at equal distances on opposite sides of the focal center point of the principal axis of the reflector.

Neither filament is at, but both are close to and on opposite sides of, the focus of the reflector.

Accordingly when either filament is made 5 incandescent, it gives a brilliant white light, but, owing to the fact that it is out of focus, the emitted light rays are sufficiently scattered and dispelled so as not to be dazzling or blinding to a person in front of the head-light.

On the other hand, when both filaments are heated at the same time, they supplement and complement one another, producing in some degree, owing to their nearness to one 15 another and because of their contiguity and proximity to the focus of the reflector, in effect a single resultant filament at the focal center with the consequent concentrated brilliant light required at times and which 20 would not be suitable for city or town driving.

For the control of the electric heating of such filaments singly or combined the appliance is provided with the three wires 18, 25 19 and 20, the wire 18 being connected to both filaments, the wires 19 and 20 being connected to the other ends of the filaments and to two terminals 21 and 22 of an electric switch 23 connected by a wire 24 to the 30 source of electric current associated with wire 18. Switch 23, consisting of a conducting straight arm with an arcuate end portion, may be shifted to cause such curved part to contact with either terminal 21 or 35 22 and cause the incandescence of either one

of the pair of filaments or it may connect with both terminals at the same time, the curved part being of sufficient length to engage both switch terminals 21 and 22 concurrently, causing the simultaneous heating 40 of the two filaments.

While I have herein described and in the drawing have illustrated a single preferred embodiment of the invention, those skilled in this art will understand that the invention is susceptible of a variety of embodiments and is not limited and restricted to the precise and exact mechanical details presented since these may be modified within comparatively wide limits without departure 50 from the substance and essence of the invention and without the sacrifice of any of its substantial benefits and advantages.

I claim:

In a head-light construction of the character described, the combination of a reflector, a multiple-filament electric-lamp bulb, and a single plug and associated socket to hold said bulb in said reflector, said bulb having two substantially-parallel closely- 55 adjacent concentrated filaments directly opposite one another on opposite sides of the axis of the reflector at the focus thereof and equally distant from such focus, said filaments being adapted to be rendered independently or simultaneously luminous and each having reflective action over the entire 60 surface of the reflector.

HARVEY H. SLATER.
